TYPOGRAPHICAL SLUG CASTING
MACHINE

John Robert Cory, Chesterfield, England, assignor
to Linotype and Machinery Limited, London,
England, a limited-liability company

Application August 3, 1940, Serial No. 350,703
In Great Britain July 25, 1939

5 Claims. (Cl. 199—51)

This invention relates to typographical slug casting machines such as those known commercially under the registered trade-mark "Linotype", and more particularly to machines provided with quadding and centering attachments, which may be set so that either or both of the vise-jaws, between which a composed line of matrices is clamped during the casting operation, will be automatically moved inwards to close on to a line of less length than that for which the jaws are set.

In mechanism of this kind inward and outward movement of the jaws is controlled by means of a cam acting upon a reciprocating rod to which the jaw or jaws are connected as desired through a system of levers. Subsequently to the quadding movement, the composed line is justified by means of a justification bar which rises and spreads the spacebands in the line to the appropriate extent for justification of the line.

The vise-jaws are normally set for the length of slug which it is desired to cast for a given column width and the quadding mechanism is out of action until it is rendered operative by an appropriate setting of a quadder control lever or the like. However, when setting up short paragraphs each consisting of a few lines of standard length and a short lastline, termed a break line, it is convenient to provide for the quadding of the break lines without necessitating repeated adjustments of the quadder control lever, and this may be accomplished by mechanism which, while permitting the quadder control lever to be set in an active position, prevents operation of the quadder except when the length of the composed line is less than the standard length by an amount which cannot be made up by the expansion of the spacebands during justification. In the employment of arrangements of this kind, there is a risk that the quadder will come into action on lines intended to be of full length, lines of irregular length being thus produced.

The object of the present invention is to provide improved mechanism which will enable justified matter of regular or normal line length to be composed irrespective of the setting of the quadding attachment.

A further object of the invention is to obtain the same and equal word spacing for all quadded lines.

According to the invention the cycle of operations in a typographical slug casting machine

provided with a quadding and centering attachment is so arranged that justification of the composed lines of matrices and spacebands takes place prior to the operation of the quadding mechanism so that a line is spread out to its maximum extent before any quadding operation can take place. Should the line not be spread out to the normal length for which the vice-jaws are set, it is then automatically quadded and the word spacing for all quadded lines will remain 10

5 the same. A preferred form of apparatus for carrying out the invention and a method of operating same are hereinafter described with reference to the accompanying drawing, which shows in side 15 elevation the relevant parts of a typographical slug casting machine.

The mechanism illustrated embodies the known form of quadding mechanism in which the vise-jaws or a selected vise-jaw are moved inwardly for centering or quadding by the downward movement of a quadder control rod 1. Only one of the vise-jaws and one of the two sets of levers and links by which the same are connected to the quadder control rod are represented in the drawing, 2 being the vise-jaw and 3, 4 the link and lever which latter is connected to the control rod 1 when desired by appropriate adjustment of the control rod collar 5. The quadding operation is controlled by a cam 6 secured to the main cam shaft 7 of the machine, this quadder cam being connected to the quadder control rod 1 by lever members 8, 9 and 10 and link 11. The lever arm 9 is under the influence of a spring 12 tending to move the quadder control rod 1 to its inactive position, and is actuated against the action of said spring to render the quadder control rod operative, by the cam controlled lever arm 8 through a plunger 13 acting on a spring 14.

The justification mechanism comprises a cam 15 mounted on the cam shaft 7, a lever 16 and a spring 17 constantly urging a roller 18 on lever 16 towards the operative surface of the cam 15.

A bar 19 is moved upwardly to effect justification by expansion of the spacebands in the composed line, said upward movement being controlled by the lever 16 through a pair of justification rods of which one only, identified by the reference 50 numeral 20, is illustrated in the drawing. As thus far described, the quadding and justifying mechanisms are substantially of known form, the normal operation of which, hereinbefore briefly referred to, is well understood.

In carrying out the invention with the constructional form of mechanism now under review, the shape of the cam 6 is altered by removing a section of its operative portion which normally 5 extends between the chain line 21 and the full line 22, so as to retard the closing of the vise-jaw or jaws set for quadding or centering until after justification, controlled by the depression 10 23 of the cam 15, has taken place.

10 The method of carrying out the invention with the apparatus above described, can now readily be understood, bearing in mind that in the drawing the quadding and justification levers are 15 shown in their normal inactive position and the cams are represented in a position reached at an intermediate stage of a single rotation of the cam shaft 7 controlling one operative cycle of the machine. At said stage of the machine cycle, a composed line of matrices and spacebands has 20 been presented between the vise-jaws 2 which are fully open, the quadder control rod 1 being in its inactive position. Continued rotation of the cam shaft to carry the cams in clockwise direction as indicated by the arrow in the drawing, presents the depression 23 of the justification cam 15 to the roller 18, and the usual initial upward movement of the justification lever 16 and bar 19 takes place to spread the line by expansion of the spacebands. Immediately thereafter 25 the quadder cam surface 22 comes into operation on the lever 8 to effect the quadding operation. If, however, the line has been fully spread against the vise-jaws which, during the just-mentioned 30 rise of the justification bar 19, were held against their respective banking abutments according to the length of line for which they are set, then the jaw or jaws selected for quadding or centering will be prevented from moving inwardly, and the justification bar rises in known manner a 35 40 second time for the second justification when the depression 24 of the justification cam reaches the roller 18. The line spread to the full length will be thus locked and a justified line of regular or normal length will be obtained. When, however, there are insufficient spacebands to spread the line to the full extent when the depression 45 50 55 60 23 is operative, the jaw or jaws selected for quadding or centering will move inwardly and the line will be automatically quadded or centered. In this case, as the spacebands will have been spread to their full extent, the word spacing of all quadded lines will be the same and equal.

55 From the position of the normal operative cam surface 21 indicated on the drawing it will be clear that the removal of a portion of an existing quadder cam to bring that operative surface to the full line position 22, is sufficient to cause the justifying mechanism to act in advance of the quad-

ding mechanism in the cycle of operations. The invention could also be carried out, however, by modifying the cam controlling the justification mechanism to secure a corresponding advance of the justification operation, and it is to be understood that the invention includes any convenient arrangement providing for the justification to be effected prior to the quadding. 5

Having described my invention, I declare that what I claim and desire to secure by Letters Pat- 10 ent is:

1. In a typographical slug casting machine, the combination of quadding mechanism adapted to effect inward movement of a line clamping jaw towards a composed line of matrices and spacebands, justifying mechanism adapted to expand the spacebands to justify the composed line, and actuating means for said mechanisms operable automatically during each machine cycle to expand the spacebands in the composed line prior 20 to the inward movement of the line clamping jaw. 15

2. In a typographical slug casting machine, the combination of quadding mechanism adapted to effect inward movement of a line clamping jaw towards a composed line of matrices and spacebands, justifying mechanism adapted to expand the spacebands to justify the composed line, a cam controlling the actuation of the quadding mechanism, a cam controlling the actuation of the justifying mechanism, and a cam shaft on 30 which said cams are relatively positioned so as to bring about actuation of the justifying mechanism prior to the actuation of the quadding mechanism during the rotation of the cam shaft controlling one operative cycle of the machine. 35

3. In a typographical slug casting machine, the combination of quadding mechanism adapted to effect inward movement of a line clamping jaw towards a composed line of matrices and spacebands, justifying mechanism adapted to expand the spacebands to justify the composed line, a cam shaft controlling one operative cycle of the machine, a cam mounted on said shaft controlling the actuation of the justifying mechanism, and a cam mounted on said shaft controlling the 40 45 50 55 60 actuation of the quadding mechanism and shaped so as to retard the inward movement of the line clamping jaw until after justification.

4. A method of operating a typographical slug casting machine provided with a quadding and centering mechanism, in which a line of matrices and spacebands is justified and spread out to its maximum extent by expansion of the spacebands and is subsequently quadded or centered. 55

5. A method of operating a typographical slug casting machine provided with a quadding and centering mechanism, in which a line of matrices and spacebands is justified and spread out to its maximum extent by expansion of the spacebands and is subsequently quadded or centered. 60
